UNITED STATES PATENT OFFICE.

CHRISTIAN HANSEN AND ANTON WEINDEL, OF LEVERKUSEN, NEAR COLOGNE, GERMANY, ASSIGNORS TO SYNTHETIC PATENTS CO., INC., OF NEW YORK, N. Y., A CORPORATION OF NEW YORK.

PROCESS FOR PRODUCING ACETIC ACID FROM ACETYLENE BY ELECTROLYSIS.

1,159,376.

Specification of Letters Patent.

Patented Nov. 9, 1915.

No Drawing.

Application filed January 28, 1914. Serial No. 815,017.

To all whom it may concern:

Be it known that we, CHRISTIAN HANSEN and ANTON WEINDEL, citizens of the German Empire, residing at Leverkusen, near 5 Cologne-on-the-Rhine, Germany, have invented new and useful Improvements in Processes for Producing Acetic Acid from Acetylene by Electrolysis, of which the following is a specification.

10 Our present invention relates to a new and valuable process of producing acetic acid from acetylene by electrolysis.

This process consists in oxidizing acetylene on the anode with the aid of an acid electrolyte, such as sulfuric acid, phosphoric acid, which contains mercury compounds.

15 The mercury is added advantageously in the form of mercuric oxid, either to the acid electrolyte directly, or in a dissolved condition.

20 When acetylene is conducted into such an acid electrolyte containing a mercury compound, addition compounds are formed which by electrolysis at the anode are oxidized to form acetic acid and set free mercury salts. The oxidation of the anode apparently results in the formation of mercury oxid which is immediately dissolved in the acid solution. Dilute sulfuric acid itself 25 possesses but little absorptive power for acetylene, but with the mercury present and the formation of the addition combinations, the absorption power of the electrolyte is increased to a remarkable degree. A good 30 yield of acetic acid is obtained, working even with the usual current at a tension of 3 to 4 volts.

35 In order to illustrate the new process more fully the following example is given, the 40 parts being by weight:—The anode-space of an electrolyzing chamber provided with a diaphragm of clay and an anode of platinum is charged with sulfuric acid (30 per cent.) and 1 to 2 per cent. of mercuric oxid 45 calculated according to the weight of the anodic liquid while the cathode formed of

lead or copper is also immersed in sulfuric acid (30 per cent.). Acetylene is then introduced into the anode's space, allowing the electric current to pass through and stirring 50 at the same time. In this process 48.5 parts of acetylene are used every hour for every 100 ampère current. The tension of the bath at a current density of 5—15 ampère for each 20 square decimeters anode's surface is 55 3—4.5 volts and the temperature of the electrolyte is kept at 30—40° C.

A good yield of acetic acid is thus obtained which can be separated from the resulting mixture in any suitable manner. 60

We claim:—

1. The process of producing acetic acid from acetylene by electrolysis which comprises the oxidation of acetylene on the anode with the aid of an acid electrolyte 65 which contains a mercury compound, substantially as described.

2. The process of producing acetic acid from acetylene by electrolysis which comprises the oxidation of acetylene on an 70 anode from platinum with the aid of a sulfuric acid electrolyte which contains a mercury compound, substantially as described.

3. The process of producing acetic acid from acetylene by electrolysis which comprises the oxidation of acetylene on the 75 anode with the aid of an acid electrolyte containing in solution about 1 to 2 per cent. of mercuric oxid.

4. The process of producing acetic acid 80 from acetylene by electrolysis which comprises the oxidation of acetylene on the anode with the aid of a sulfuric acid electrolyte which contains a mercury compound, substantially as described. 85

5. The process of producing acetic acid from acetylene by electrolysis which comprises the oxidation of acetylene on the anode with the aid of a sulfuric acid electrolyte of about 30 per cent. sulfuric acid 90 which contains a mercury compound, substantially as described.

6. The process of producing acetic acid from acetylene by electrolysis which comprises the oxidation of acetylene on the anode with the aid of a sulfuric acid electrolyte of about 30 per cent. sulfuric acid containing in solution about 1 to 2 per cent. of mercuric oxid.

In testimony whereof we have hereunto

set our hands in the presence of two subscribing witnesses.

CHRISTIAN HANSEN.
ANTON WEINDEL.

Witnesses:

LOUIS VANDORY,
HANS BRICKNER.

It is hereby certified that in Letters Patent No. 1,159,376, granted November 9, 1915, upon the application of Christian Hansen and Anton Weindel, of Leverkusen, near Cologne, Germany, for an improvement in "Processes for Producing Acetic Acid from Acetylene by Electrolysis," an error appears in the printed specification requiring correction as follows: Page 1, line 31, after the word "mercury" insert the word *compound*; and that the said Letters Patent should be read with this correction therein that the same may conform to the record of the case in the Patent Office.

Signed and sealed this 18th day of January, A. D., 1916.

[SEAL.]

J. T. NEWTON,

Acting Commissioner of Patents.
